UNITED STATES PATENT OFFICE.

FRANK TAYLOR AND ADDIE TAYLOR, OF BAY CITY, MICHIGAN.

HEADWEAR.

No. 813,467.

Specification of Letters Patent.

Patented Feb. 27, 1906.

Application filed June 14, 1905. Serial No. 265,210.

To all whom it may concern:

Be it known that we, FRANK TAYLOR and ADDIE TAYLOR, citizens of the United States, residing at No. 1837 Sixth street, Bay City, 5 in the county of Bay and State of Michigan, have invented new and useful Headwear, of which the following is a specification.

This invention relates generally to headwear, and particularly to a novel form of 10 poke-bonnet adapted for use at seaside resorts, although it will be found applicable for use in other localities, especially in rural districts.

The objects of the invention are to provide 15 a bonnet which while possessing all of the advantages of a poke-bonnet shall also embody characteristics common to an ordinary cap, thereby permitting a greater range of vision without necessitating the lifting of the head, 20 and, further, of securing passage of air to the sides of the head, whereby an objectionable feature to ordinary poke-bonnets is eliminated.

A further object is to dispense with the employment of strings or ribbons to secure the 25 bonnet in place upon the head of the wearer.

With the above and other objects in view, as will appear as the nature of the invention is better understood, the same consists in the 30 novel construction and combination of parts of a sunbonnet, as will be hereinafter fully described and claimed.

In the accompanying drawings, forming a 35 part of this specification, and in which like characters of reference indicate corresponding parts, Figure 1 is a view in perspective of the representation of a human figure wearing the bonnet of the present invention. Fig. 2 is a view in elevation, partly in section, of the 40 bonnet, taken from the front.

Referring to the drawings, 1 designates the peak of the bonnet, 2 the cape, and 3 the vizor. The peak and cape will, by preference, be made of a single piece of material, although they may be made of two pieces properly assembled. The material of which the peak and cape is constructed is cut in such manner as that when assembled with the vizor a full peak will be secured which will 45 prevent rumpling of the hair, will render the article more comfortable in use, and will allow of circulation of air into the peak, which is a feature of importance in warm weather. The peak and cape are, by preference, made of

a single thickness of material, while the vizor 55 is made of two or more thicknesses in order to permit of it holding a sufficient quantity of starch to render it stiff, so that in use it will occupy a position that will enable the wearer to see equally as well as if the bonnet 60 were not worn, and, further, which will allow air to pass to the face. As shown in Fig. 1, the cape is disconnected from the vizor at points slightly in advance of the ears, thereby protecting those parts of the head from 65 the direct rays of the sun, but at the same time allowing the air to pass around the ears and back of the neck. As herein shown, the vizor and peak are secured together by a felled seam 4, this for the purpose of giving a 70 finished appearance to the article and also to secure added strength. The binding 5 may be made of the same material as the bonnet or of tape or any other textile fabric desired.

As stated, it is one of the objects of the invention to dispense with the employment of strings or ribbons for securing the bonnet upon the head of the wearer, and this is accomplished by the employment of a strip of elastic 6, which is secured to the inner side of the cape on a curved line extending from the points of juncture of the vizor and cape. The elastic is secured in a pocket formed by an attached strip of tape or muslin 7, whereby it will be protected from contacting with the head of the wearer. This elastic will normally be under tension, so as to cause the base of the peak to have a tucked appearance, as shown in Fig. 1, and in use the elastic will pass around beneath the knot or twist 85 of the hair, and thereby securely position the article in place.

While the improvements herein described are simple in character, they will be found to result in the production of a highly desirable 95 and finished article of headwear and one that will be easier and cooler to wear than the ordinary bonnets in use.

Having thus described the invention, what is claimed is—

1. A bonnet embodying a one-piece peak and a cape, the latter having combined with it an elastic drawing-string, and a vizor combined with the peak and disconnected from the cape.

2. A bonnet embodying a peak and cape constructed of a single piece of relatively 105 sleazy material and having combined with it

an elastic drawing-string, and a relatively stiff vizor secured to the peak and disconnected from the cape.

3. A bonnet embodying a peak, a cape and a vizor combined with the peak and disconnected from the cape, and an elastic securing member disposed at the juncture of the peak and the cape.

4. A bonnet embodying a relatively lim-
10 ber peak and cape, and a relatively stiff vizor
combined with the peak and disconnected

from the cape at the sides, and an elastic securing member disposed on a curve at the juncture of the peak and the cape.

In testimony that we claim the foregoing ¹⁵ as our own we have hereto affixed our signatures in the presence of two witnesses:

FRANK TAYLOR.
ADDIE TAYLOR
